(57) **CLAIM**

The ornamental design for a cap with upwardly bent front visor, as shown and described.

DESCRIPTION

FIG. 1 is a front view of the cap with upwardly bent front visor;

FIG. 2 is a rear view of the cap with upwardly bent front visor;
FIG. 3 is a side view of the left of the cap with upwardly bent front visor;

FIG. 4 is a side view of the right side of the cap with upwardly bent front visor;

FIG. 5 is a top view of the cap with upwardly bent front visor;
and,

FIG. 6 is a bottom view of the cap with upwardly bent front visor.

The broken lines shown in the drawings illustrate stitching and are part of the claimed design.
